UNITED STATES PATENT OFFICE.

HARRY A. BOWER, OF BOSTON, MASSACHUSETTS.

BASS-DRUM AND CYMBAL BEATER.

No. 846,391.

Specification of Letters Patent.

Patented March 5, 1907.

Application filed October 22, 1906. Serial No. 339,895.

To all whom it may concern:

Be it known that I, HARRY A. BOWER, of Boston, in the county of Suffolk and State of Massachusetts, have invented certain new and useful Improvements in Bass-Drum and Cymbal Beaters, of which the following is a specification.

This invention has relation to instrumentalities for beating a bass drum and sounding a cymbal, and has for its object to provide a foot-actuated mechanism which may be operated to produce the same results and tonal effects as though the drumstick and the cymbal-striker were operated independently and by hand.

In many orchestras, such as those employed for theatrical and minor operatic productions, the drummer is called upon to perform upon a number of instruments in addition to the bass drum and cymbals, so that it has been heretofore recognized that the latter must be sounded by some foot-actuated instrumentalities to enable the drummer to use his hands for the snare-drum, the tympani, and other musical instruments. The foot-actuated instrumentalities or devices for sounding the bass drum and the cymbals which have heretofore been utilized or proposed have been defective, in that the drummer could not, in my opinion, produce those variations in effect which should characterize music of a high class. Again, said instrumentalities have been bulky and clumsy, so as to occupy valuable space; whereas they should be small and compact, so as to require but little room.

My invention contemplates a foot-operated instrumentality for actuating the drumstick and the striker for the cymbals by means of which the instruments may be struck with blows of varying force, so as to produce a variety of effects, such as may be called for by the score.

One of the features of the device is a foot-operated actuator by which either the drumstick, the cymbal-striker, or both, may be operated, which actuator consists of a leaf-spring bent in the form of a bow and having one end connected to a stationary support or pivot and its free end connected to the stick and the striker. Preferably there is connected directly to the convex face of the spring a plate, which constitutes a treadle, upon which the ball of the foot of the drummer may be placed. The drumstick is prefer-

ably pivoted at its end and is flexibly connected to the end of the spring, so that when the plate previously referred to is depressed by the foot of the drummer the spring is straightened out, so as to impel the free end of the stick toward the drumhead. The tension of the spring normally withholds the free end of the stick at some distance from the head and tends substantially to assume its normal curvature. I utilize this feature by attaching to the spring one or more strikers for the cymbal, so that when the foot-plate is depressed the striker or strikers are caused to impinge upon the cymbal, which is properly located with reference thereto.

Referring to the accompanying drawings, Figure 1 represents one embodiment of the invention. Fig. 2 represents a section on the line 2 2 of Fig. 1 looking in the direction of the arrow. Fig. 3 represents a section on the line 3 3 of Fig. 1. Fig. 4 represents a section on the line 4 4 of Fig. 3. Fig. 5 illustrates how the cymbal-strikers are mounted. Fig. 6 represents a plan view of the base partially in section with the spring-actuator cut away.

Referring to the drawings, it will be seen that the device or appliance includes a base which is adapted to rest upon the floor. This comprises a longitudinal bar 10, having at one end an adjustable extension 11. The extension 11 is bent upwardly at its end and is provided with a curved cross-piece 13, which serves as a rest, support, or abutment for the heel of the drummer's shoe. At the right-hand end of the bar 10 are two adjustable clamp members 12 and 14, which are bent upward and toward each other to embrace the hoop of the drum, as shown in Fig. 1. The clamp member 12 is somewhat wider than the bar 10, as shown in Fig. 6, and it is provided with lugs 16, which embrace the side edges of the bar 10. The members 12 and 14, as stated, are adjustable longitudinally of the bar 10 and relatively to each other and are slotted to receive a bolt 17 and wing-nut 18, by which they and the bar are securely clamped together. At 42 is a cross-bar having its corners bent down and which serves to keep the base flat on the floor. Said cross-bar is secured to the bar 10 by a bolt 43 and wing-nut 44. The bars 10, 11, 12, and 42 therefore constitute a base for the operative parts of the appliance.

Extending laterally from the bar 10 there is another bar 19, which is secured to the bar

10 by a bolt 20 and a wing-nut 21. The bar 19 is provided at its end with a cross-piece 22 with its corners bent down to engage the floor, as illustrated in Figs. 2 and 6.

5 A bolt 23 projects upwardly through the bar 19 and the cross-piece 22, and a nut 24, in threaded engagement with said bolt, securely binds the parts 19 and 22 together. Said bolt 23 serves to support the cymbal, as will 10 be subsequently explained. The lateral bar 19 may be swung about the bolt 20 as a pivot to move the cymbal into and out of coactive relation with the striker; but in addition to its function of supporting the cymbal it also 15 serves to steady the bar 10 and hold upright the parts which are supported thereby. The bars 10, 11, 12, and 14, the rest or abutment 20 13, and the cross-piece 22 are all preferably formed of strap metal of sufficient thickness and rigidity to stand the strain to which they are subjected.

The drumstick 25 is pivotally connected to the end of the bar 10. To accomplish this, there is riveted to the said bar a metallic 25 yoke 26, in which there is a pivot or fulcrum pin 27 to receive a second yoke 28. To the yoke 28 there is secured a third yoke 29, one of the sides of which is riveted or otherwise secured to the back of the yoke 28. The 30 sides of the yoke 29 and the back of the yoke 28 are apertured to receive the end of the stick 25. A bent spring 30, one end of which is attached to the back of the yoke 29, bears against the stick between the sides of the 35 yoke 29, so as to prevent its dislocation. These parts, with the exception of the spring, are formed or made of metallic straps substantially similar to those of which the base is formed.

40 The actuator consists of a curved leaf-spring 31. Its left end, which is bifurcated, is pivotally coiled around a transverse pin or pivot 32, secured to the bar 10 by the bolt and wing-nut 43, 44, and its free end is secured to a loop 33, of flexible material, such as soft leather. This loop is secured to the upper side of the yoke 29 and it is apertured to receive the stick 25. To the convex face 45 of the spring 31 there is secured a plate 34 to receive the ball of the foot of the drummer, so that when the heel of his foot is placed against the rest 13 and the plate is depressed the spring 31 will be straightened out, as illustrated in dotted lines, so as to force the 50 free end of the stick 25 toward the drum-head. The spring normally tends to contract to the full-line position in Fig. 1, so as to withdraw the free end of the stick from the drum-head, which is indicated at *a*.

55 The cymbal is illustrated at *b* in Fig. 2, and it is secured upon the bolt 23 by a nut 35, washers 36, and a wing-nut 37. I preferably employ a plurality of strikers for the cymbal, said strikers consisting of metallic fingers 38 60 38, the free ends of which diverge, as illus-

trated in Fig. 5. These fingers are pivoted upon a wire yoke 39, attached to a bracket 40, secured to the under side of the spring 31 by bolt 41 and wing-nut 42. When the spring 31 is in its normal position, the fingers 38 are elevated above the edge of the cymbal; but when the spring is straightened out and its curvature is reduced the pins 38 will impinge upon the edge of the cymbal. The various fingers are free to vibrate independently of each other, and to this end their inner ends are encircled by a band 42, of rubber, as illustrated in Fig. 5, which is passed around the yoke 39. Said strap or band further serves to hold said fingers normally 80 in the same plane and laterally outward from the spring.

To limit the downward movement of the body of the spring, I place below it and in the arc of movement of the plate or treadle 85 34 a stop consisting of a bracket 50, secured in place by the bolt 20 and wing-nut 21 and shod with soft cushioning material, as indicated at 51.

It will be understood that the device here- 90 in illustrated and described is not the only embodiment of the invention and that various changes in the construction and arrangement of the details thereof may be made without departing from the spirit and scope 95 of the invention.

Having thus explained the nature of the invention and described a way of constructing and using the same, although without attempting to set forth all of the forms in 100 which it may be made or all of the modes of its use, I declare that what I claim is—

1. In a device of the character described, a drumstick, and an actuator therefor comprising a curved spring having one end stationary and the other end connected to the stick, said spring being adapted to be engaged between its ends to effect the actuation of the stick thereby.

2. In a device of the character described, a 110 base, a drumstick pivotally connected to the base, and a curved spring having one end connected to the base and the other end connected to the stick, whereby pressure upon the spring effects the actuation of the stick.

3. In a device of the character described, a base, a drumstick pivotally connected to the base, a curved spring having one end connected to the base and the other end connected to the stick, and a foot-piece secured 120 to the curved face of the spring between its ends.

4. In a device of the character described, a base having a transverse pivot-pin, a curved spring pivoted upon said pivot-pin, a drum- 125 stick, means for pivotally connecting said stick to said base, and means for flexibly connecting the free end of said spring to said stick.

5. In a device of the character described, a 130

base, a drumstick pivotally connected to the base, a curved spring having one end connected to the base and the other end connected to the stick for actuating the stick, and a stop for limiting the movement of the spring.

6. In a device of the character described, a base adapted to rest upon the floor and having clamp members at one end for engagement with a drum and an abutment or rest at the other end for the heel of the drummer's foot, a curved spring connected to the base and extending toward the clamp members, a foot-plate attached to the convex face of said spring; and a drumstick pivotally connected to the base at a point adjacent the clamp members and connected to said spring.

7. In a device of the character described, the combination with a cymbal, of means for sounding the cymbal, comprising a curved spring, one or more strikers extending laterally from said spring and adapted to impinge upon the cymbal, and means for yieldingly mounting said striker or strikers on said spring.

8. In a device of the character described, a curved spring secured at one end and having its other end free, means for guiding the free end of the spring, and one or more cymbal-strikers projecting laterally from said spring between its ends.

9. In a device of the character described, a base, an actuator connected to said base, a pivot connected to the actuator, and a plurality of diverging cymbal-strikers mounted

upon said pivot, and means for yieldingly holding said strikers in operative position.

10. In a device of the character described, the combination with a base, and an actuator connected thereto, of a bracket on the actuator having a yoke, one or more strikers pivoted on said yoke, and an elastic band around said yoke and the inner ends of said strikers substantially as set forth.

11. In a device of the character described, a base, a drumstick pivoted to said base, a curved spring connected to said base and said stick for actuating the latter, a lateral extension of said base for supporting a cymbal, and one or more strikers on said spring for engaging the cymbal.

12. In a device of the character described, a base, a drumstick pivoted to said base, a lateral extension of said base upon which a cymbal may be supported, means on said base by which it may be connected to a drum, a curved spring loosely connected to the base and to the drumstick, one or more cymbal-strikers on the said spring, and a heel-rest on the base in such relation to the spring that the said spring may be depressed by the foot of the drummer when his heel is against said rest.

In testimony whereof I have affixed my signature in presence of two witnesses.

HARRY A. BOWER.
